(57) **CLAIM**

I claim the ornamental design for a wearable article for tracking medical-related events, as shown and described.

DESCRIPTION

FIG. 1 is a front perspective view of a wearable article for tracking medical-related events of the present disclosure; FIG. 2 is a top view of the wearable article for tracking medical-related events of FIG. 1;

FIG. 3 is a bottom view of the wearable article for tracking medical-related events of FIG. 1;

FIG. 4 is a front view of the wearable article for tracking medical-related events of FIG. 1;

FIG. 5 is a back view of the wearable article for tracking medical-related events of FIG. 1;

FIG. 6 is a right side view of the wearable article for tracking medical-related events of FIG. 1; and,

FIG. 7 is a left side view of the wearable article for tracking medical-related events of FIG. 1.
